BURIAL VAULT

Joseph A. Patterson, Brave, Pa., assignor of
three-fourths to The Patterson Burial Vault
Trust, Brave, Pa.

Application March 4, 1939, Serial No. 259,892

4 Claims. (Cl. 72—7)

This invention relates to a burial vault of the type for use in a grave for enclosing a coffin and it is one object of the invention to provide a vault including a base and a body for resting upon the base about a coffin, the base and body being both formed of concrete and having means associated therewith for excluding water and thus preventing water from seeping into the closed vault and accumulating therein about the 10 coffin.

Another object of the invention is to so form the base and walls of the body of the vault that when the body is applied to the base in enclosing relation to a coffin resting upon the bed portion of the base, the bed will be surrounded by asphalt and asphalt between the bed and margins of the base compressed by walls of the body or cover and caused to merge with a layer of asphalt embodied in the body. It will thus be seen that a sealed joint will be formed and, although water may penetrate outer portions of the body and portions of the base below the supporting bed for the coffin, further inward seepage of water will be stopped and the interior of 25 the vault maintained in a dry state.

Another object of the invention is to provide improved means for reinforcing the base and body or cover of the vault, which means are formed of concrete and, in addition, provide the base and body with hangers projecting therefrom for engagement with grapples of a hoist so that the heavy base and body may be safely lifted and lowered into a grave.

Another object of the invention is to so form and mount the hangers that they will be secured to the reinforcements and each other and strain evenly distributed throughout the base and body as they are lowered into the grave.

The invention is illustrated in the accompanying drawings, wherein:

Fig. 1 is a perspective view of the improved vault showing the body or cover about to be set in place upon the base.

Fig. 2 is a transverse sectional view taken vertically through the vault with a coffin enclosed therein.

Fig. 3 is a fragmentary perspective view showing a portion of the reinforcement for the body and one of the hangers carried thereby.

Fig. 4 is a fragmentary sectional view showing the body about to be set in place upon the base.

Fig. 5 is a fragmentary sectional view similar to Fig. 4, but showing a modified construction.

Fig. 6 is a sectional view showing the vault

body of Fig. 5, in its fully lowered or closed position.

This improved vault consists of a base 1 formed of concrete and a body or cover 2 which is also formed of concrete and, when in position, rests upon marginal portions of the base in enclosing relation to a coffin 3 resting upon the transversely extending ribs 4 of a concrete bed 5 constituting an element of the base but formed separate therefrom.

The base 1 has its under face formed with a recess 6 defining depending marginal portions 7 extending entirely about the base and in these marginal portions are embedded reinforcing rods or bars 8 and 8', which greatly strengthen the 15 same and prevent cracking thereof. The base is also reinforced throughout its area by a woven wire reinforcement 9 which is curved downwardly through the marginal portions 7 and anchored to the bars 8'. Pockets 10 are formed in the 20 upper face of the base to receive portions 11 of the layer of asphalt 12 with which the base is covered, it being understood that the pockets are preferably a multiplicity of individual pockets spaced from each other throughout the area 25

of the base, but may be intersecting grooves extending longitudinally and transversely of the base, if so desired. Hangers 13, of inverted U-shape formation and formed of heavy wire or light rod metal, are disposed at opposite sides 30 of the base in spaced relation to each other longitudinally thereof. These hangers have lower portions of their arms bent inwardly and terminating in hooks 14 which engage about the bars 8' and firmly anchor the hangers to the reinforcing bars in an upright position with their upper portions projecting upwardly from the base a sufficient distance to overlap side walls of the body 2 of the vault, as shown in Fig. 2. These hangers are for engagement by grapples of a derrick employed as means for lifting the heavy concrete base and lowering it into a grave. The hangers will also be made use of when lifting the finished base from the mould in which it is 35 formed.

After the concrete base has set and the asphalt layer 12 has been applied thereto, the concrete bed 5, which is reinforced by an embedded wire reinforcement, is set in place upon the layer of asphalt and marginal edges of the bed are covered with asphalt, as shown at 16, and, in the preferred embodiment of the invention, upstanding ribs 17 are formed on the layer of asphalt about the base in spaced relation to the facing 50 55

16 of the bed and margins of the base, as shown in Figs. 1 and 4 of the drawings.

The body or cover 2 of the vault, which is also formed of moulded concrete, has inner and outer sections 18 and 19, reinforced by embedded interwoven wire reinforcements 20 and 21. Between the sections 18 and 19 of the body is a layer 22 of asphalt, which covers the entire outer surface of the inner section 18 and constitutes a waterproof layer which will prevent water from seeping through the inner section, even if water should pass through the outer section 19. Lower edge portions of confronting faces of the inner and outer sections 18 and 19 diverge, as shown in Fig. 4, to form a channel or pocket 23 to receive the upstanding asphalt ribs 17 of the base, and attention is called to the fact that the open mouth of the lower end of the pocket 23 is somewhat wider than the width of the base of the ribs 17 so that when the body is applied to the base, the ribs may expand transversely in the pocket and completely fill the same while merging with the layer of asphalt 22, as shown in Fig. 2. The inner section 18 is also formed entirely about lower edges of its walls with a recess or channel 24, and from an inspection of Figs. 2 and 4, it will be seen that when the body of the vault is lowered into place upon the base, the upper edge 25 of the pocket will engage the asphalt facing 16 and exert a cutting and scraping action which will displace portions of the asphalt and force the same downwardly and outwardly to fill the pocket 24, as shown at 26 in Fig. 2. A portion of this displaced asphalt will also be forced outwardly to assist in filling the pockets 23. It will thus be seen that a thoroughly waterproof joint will be formed between the lower edge faces of the walls of the body 2 and marginal portions of the base and water will be prevented from working inwardly between the same as well as being prevented from reaching the bed 5 or the inner section 18 of the body and seeping through the same into the vault, in the event water seeps through the base of the outer section 19 of the body.

The body of the vault is very heavy since it is formed of concrete, and in order to permit it to be lifted and lowered into place about the coffin 3, there have been provided hangers 27. These hangers are of an inverted U-shape formation and each is formed from a strand of heavy wire or light rod metal, as shown in Fig. 3. The hangers 27 extend vertically in side walls of the body with their upper end portions protruding at opposite sides of the dome-shaped portion 28 thereof, and lower end portions of the arms of the hangers are bent laterally therefrom, as shown at 29, to form base portions which terminate in hooks 30 engaged about strands of the wire reinforcement 21 of the outer section 19 of the body. The arms and base portions of the hangers are crimped, as shown at 31, to assist in holding the hangers in the concrete from which the body is formed, and in order to more evenly distribute strain when lifting the body with a derrick having grapples engaged in the protruding upper ends of the hangers, there have been provided tie rods or wires 32 which extend about the body, as indicated by dotted lines in Fig. 1, with their ends terminating in hooks 33 engaged with certain of the crimps 31.

When the improved vault is in use, the base 1 is lowered into a grave by a crane or other hoist engaged with the hangers 13 and set in place at the bottom of the grave. The coffin is then low-

ered and brought to rest upon the ribs 4 of the bed 5 of the base, after which the body or cover 2 is lifted by its hangers 27 and lowered into the grave until it comes to rest upon the projecting marginal portions of the base. As the body or cover is lowered into place, portions of the asphalt facings for the sides and ends of the bed will be displaced and shifted into the pockets 24 to fill the same and the ribs 17 will be compressed into the pockets 23 to completely fill the same and merge with lower marginal portions of the asphalt layer 22 of the body. The base and outer section of the body will thus be entirely separated from the bed 4 and the inner section of the body by asphalt and, consequently, water will be very effectively excluded from the interior of the vault. Therefore, the coffin resting upon the bed 4 and enclosed in the vault may not be damaged by water seeping through concrete from which the base and the two sections of the body are formed.

Instead of forming the body with a deep and upwardly tapered pocket 23 to receive ribs 17, the lower edge faces of walls of the two sections of the body may be shaped to define a shallow recess or pocket 34 which extends entirely about the body and has an arcuate upper wall, as shown in Figs. 5 and 6. The surface 35 surrounding the channel or pocket 34 is in a somewhat higher plane than the surface 36 between the channel 34 and the channel 24. The asphalt coating 12, instead of being formed with ribs 17, has its marginal portions formed with a shallow channel 37, and when the body is set in place upon the base, the asphalt is displaced and subjected to pressure to fill the channel 24 and also fill the channel 34, as shown in Fig. 6, where a portion of the asphalt has been shown projecting upwardly into the channel 34, as indicated at 38, and merging into lower edge portions of the layer of asphalt 22 to form a sealed waterproof joint between the base and the body or cover of the vault.

Having thus described the invention, what is claimed is:

1. In a burial vault, a base, a bed associated with said base for supporting a coffin and disposed over the base with its sides and ends spaced from the margins of the base, and a cover for enclosing the coffin having a top and side and end walls resting upon the base about margins of said bed, said cover having inner and outer sections and a layer of plastic water proof material between the same, and said base having a layer of plastic water proof material separating the base from the bed and extending outwardly from the bed under walls of the cover to margins of the base, a portion of the plastic water proof material under the walls of the cover merging with the plastic water proof material between the sections of the cover to unite therewith and form a sealed water-tight joint between the base and cover for excluding water from the vault.

2. In a burial vault, a base, a bed for supporting a coffin having its margins spaced from margins of the base, a layer of plastic water proof material between the base and the bed having portions covering edge faces of the bed and other portions extending about the bed and formed with upstanding ribs surrounding the bed in spaced relation thereto, and a cover for fitting about said bed consisting of inner and outer sections and a layer of plastic water proof material between said sections, the plastic water proof material covering edge faces of said bed forming a water tight joint between the bed and the con-

fronting faces of walls of the cover, and lower edge portions of confronting faces of said sections being shaped to define a pocket for receiving said ribs and effecting a watertight joint by merging of the ribs with the plastic water proof material between the sections.

5. In a burial vault, a concrete base, a concrete bed over said base for supporting a coffin, a layer of plastic water repelling material between the 10 base and said bed extending outwardly between the bed and margins of said base with portions covering edge faces of the bed and other portions forming upstanding ribs spaced from margins of the base, and a cover for enclosing the bed and 15 a coffin thereon consisting of inner and outer sections and a layer of plastic water repelling material between the sections, confronting portions of said sections below the intervening asphalt defining pockets exposing the plastic water repelling 20 material and adapted to receive said ribs and compress the ribs into merging engagement with the plastic water repelling material between the sections, and said inner section having its lower edge portion formed with a circumscribing pocket 25 adapted to be filled with plastic water repelling material scraped from asphalt covering side edges of the bed by the inner section when the cover is set in place about the bed.

4. In a burial vault, a base having its upper face formed with pockets, a bed over said base for supporting a coffin, a layer of plastic water repelling material between the base and bed having anchoring portions filling said pockets, said plastic water repelling material having marginal portions extending from sides and ends of the bed to margins of the base and being formed with portions covering edge faces of the bed and with upstanding ribs spaced from margins of the base, 10 and a cover for enclosing a coffin having a top and side and end walls, said cover consisting of inner and outer sections and a layer of plastic water repelling material between the sections, lower edge portions of the walls of said sections 15 having confronting faces beveled to form pockets for receiving said ribs and compressing the ribs to fill the pockets and merge with the layer of plastic water repelling material between the sections of the cover, the inner section having 20 lower edge portions of its walls recessed to form a circumscribing pocket adapted to be filled with plastic water repelling material scraped from the plastic water repelling material covering edge faces of said bed by upper edges of the recesses as 25 the cover is lowered into place.
